SCREEN DOOR

John F. Walsh, Scranton, Pa.

Application January 16, 1947, Serial No. 722,319

4 Claims. (Cl. 160—31)

1

This invention refers generally to screen doors, and more particularly, to a screen door having an open frame and a sheet of foraminous flexible material mounted in an upright roller at one side of the door and extensible to close the opening of the open frame.

It is an object of this invention to provide a screen door which will allow access through the doorway either by swinging the frame of the door about a pivotal attachment securing one side of the frame to the door jamb, or by merely rolling up a screen on a roller secured in one side of an open frame.

Another object of this invention is to provide means for conveniently locking the screen in extended position.

Another object of this invention is to provide convenient means for preserving the door in closed position, that is, preserving the open frame disposed across the door jamb.

Another object of this invention is to provide convenient means for unlocking the screen from the swinging stile of the door so that the screen can be retracted.

And a last object to be specifically mentioned is to provide a device of this character which is inexpensive and practicable to manufacture, simple to install and to use, and which is sufficiently sturdy to provide for generally efficient and durable service.

With these objects definitely in view, this invention resides in certain novel features of construction, combination and arrangement of parts and portions as will be hereinafter described in detail and particularly set forth in the appended claims, reference being had to the accompanying drawings which form a material part of this application, and in which:

Figure 1 is a front elevational view of a screen door constructed according to this invention;

Figure 2 is a similar view but showing the screen retracted, to provide for free access through the door;

Figure 3 is a horizontal sectional view, fragmentary in character and enlarged, the view being taken on the line 3—3 in Figure 1;

Figure 4 is a similar view but showing the parts in the position assumed when the door frame is partially opened and the screen is completely extended;

Figure 5 is a broken vertical sectional view showing the roller and contiguous portions, the view being taken on the line 5—5 in Figure 1;

Figure 6 is a broken vertical sectional view, taken on the line 6—6 in Figure 2;

2

Figure 7 is a broken perspective view of the channel member comprising a top rail of the open frame;

Figure 8 is a broken similar view of the bottom rail;

Figure 9 is a broken view of the rule-jointed extensible arms, indicating an arm in side elevation;

Fig. 9a is a top plan view of Figure 9; and

Figure 10 is a view of the spring means whereby the door is urged into closed position, the view being technically a horizontal-sectional view taken on the line 10—10 of Figure 5.

Similar characters of reference designate similar or identical parts and portions throughout the specification and throughout the several views of the drawing.

Referring now to these drawings in detail, which drawings represent one preferred embodiment of this invention, it will be noted that a door jamb 10 having a sill 12 is shown with this improved door mounted therein. The open frame door is comprised of an upright tubular member 14 which is slotted as at 16 and provided with a tangentially disposed neck member 18 extending the full vertical height of this member 14, together with an upper rail 20 which is channeled as at 22, a swinging stile member 24, and a lower rail 26 which is channeled as at 28. The above four frame members will be integrated together as by welding to form a rectangular open frame with the channels 22 and 28 and the neck 18 all disposed towards the inside of the open frame. The tubular member 14 may be considered the hinged stile of this door and a roller 30 is mounted axially thereof by the terminal pins 32 and 34. If reference is had to Figure 10 it will be seen how the pin 32 is urged to turn in one direction by a spring 36 terminally secured to this pin 32 and to the cap-like mounting 38, which latter is embedded in and rigidly secured to the sill 12 of the door frame. Since the pin 32 is rigidly secured to the tubular member 14, it will be seen that the spring 36 is effective in urging the door into closed position.

At the upper end of the roller 30 there is provided a coil wire spring 40, one end of which is secured to the roller 30 and the other end is secured to the pin 34 and the pin 34 is mounted after the fashion of window blind rollers in a cap mounting member 42. A generally rectangular sheet of foraminous material has one edge thereof secured to the roller 30 and is adapted to be wound upon the roller by the action of the spring 40, it being understood that the tubular

member 14 is of considerably larger diameter than the roller 30 in order that sufficient space 44 is provided for the coiled portion of the foraminous sheet, hereinafter referred to simply as the screen 46. The upper and lower edges of the screen 46 slide within the channels 22 and 28, and the outer edge of the screen is secured to an irregularly shaped inflexible strap member 48, to provide sufficient rigidity to the screen and to facilitate the securement thereof in extended position. The strap member 48 is terminally engaged in the channels 22 and 28, and may be made to more freely slide therein by the provision of small rollers on the upper and lower ends thereof, these rollers being deleted from the drawing in the interest of simplicity. The strap member 48 has a reduced portion 50 and an enlarged portion 52, each coextensive with the length of the strap member, and the enlarged portion 52 is adapted to be grasped by a spring clip 54 formed integral with the swinging stile member 24. It is preferred that this spring clip member 54 should also be coextensive with the length of the stile member 24, in order that satisfactory locking action be provided over the full length of the outer edge of the screen assembly. It will also be noted that the vertical stile member 24 includes a clip member 56, disposed longitudinally on the outer edge thereof and adapted to engage an elongated U-shaped lock member 58, vertically secured by screws 60 to an inner face of the door jamb 10.

In order that the screen 46 may be conveniently held in extended position, two pairs of arms 62-68, connected by rule joints 70 and 72, and terminally secured to the neck portion 18 and the stile member 24, are spaced apart as shown in Figure 1 with a connecting link 74 secured therebetween in order that a knob member 76, pivotally mounted on the stile member 24 may be used to actuate all the said arms simultaneously in releasing the arms from their horizontal or locked position, it being only necessary to turn the knob 76 so that the rule joints 70 and 72 are raised.

The operation of this device may be inferred from the foregoing description of the mechanical details thereof but, in recapitulation, it may be well to note that the door can be used in a substantially conventional manner with the clips 56 and 58 acting as locking members to hold the frame in place, and the door being openable by simply pulling these locking members out of engagement and pivoting the complete assembly on the pivot pins 32 and 34. The door 10 also can be used in another manner, the open frame being allowed to remain stationary and the knob 76

turned to release the locking arms 62-68, whereupon the spring 40 will cause rotation of the rollers 30 and the retraction of the screen 46 into the tubular member 14, the arms collapsing as indicated in Figure 2.

Many and various minor modifications may be made in this invention without departure from the spirit thereof and though there has been shown a particular embodiment of this invention, this application is not limited to this particular embodiment, but it is desired to include in the scope of this invention the construction, combination and arrangement of parts and portions substantially as set forth in the appended claims.

What is claimed as new and desired to be secured by Letters Patent is:

1. A screen door comprising an open frame having a top rail and a bottom rail, a swinging stile and a hinged stile, said hinged stile having a spring loaded vertical roller, a sheet of foraminous flexible material secured at one side to said roller, a non-flexible strap secured to the opposite side of said screen, and channels in said top and bottom rails to receive and to guide the ends of said strap, whereby said screen is retractably extensible across said open frame.

2. A screen door comprising an open frame including, a swinging stile and a hinged stile, said hinged stile having a spring loaded vertical roller, a sheet of foraminous flexible material secured at one side to said roller, a non-flexible strap secured to the opposite side of said screen, and means to retractably extend said sheet across said open frame, and a latch to detachably lock said strap on said swinging stile.

3. A screen door according to claim 1 and in which said hinged stile is tubular and longitudinally slotted with said roller rotatably mounted therein.

4. A screen door according to claim 1 and including extensible rule jointed arms secured to said hinged stile and to said strap said arms when extended comprising means to lock the screen in extended position.

JOHN F. WALSH.
